United States Patent Office

Des. 184,506
Patented Mar. 3, 1959

184,506

DOOR PULL OR SIMILAR ARTICLE

Jake Borenstein, Los Angeles, Calif., assignor to Jaybee Manufacturing Corporation, Los Angeles, Calif., a corporation of California

Application December 13, 1956, Serial No. 44,192

Term of patent 14 years

(Cl. D50—6)

FIG. 1.

FIG. 2.

FIG. 3.

FIG. 4.

FIG. 5.

Figure 1 is a side elevation of a door pull or similar article embodying my new design;

Fig. 2 is a front elevation taken from the right of Fig. 1;

Fig. 3 is a top plan view;

Fig. 4 is a rear view; and

Fig. 5 is a front perspective view thereof.

I claim:

The ornamental design for a door pull or similar article, substantially as shown.
